BUTTON SEWING MACHINE

Joseph H. Plikul, Boston, Mass., and Samuel W. Avis, Providence, R. I., assignors to The Reece Button Hole Machine Company, Boston, Mass., a corporation of Maine

Application January 5, 1938, Serial No. 183,480
In Great Britain February 24, 1936

13 Claims. (Cl. 112—110)

This invention relates to machines for sewing on buttons, and especially to automatic machines for sewing substantially flat buttons having each two pairs of thread-receiving perforations or holes through each of which pairs a group of attaching stitches is passed. The present case is a continuation in part, and with respect to common subject matter, of our prior application filed September 30, 1936, Serial No. 103,326.

In single needle machines for automatically sewing a four-hole button in one cycle of operation, the sewing through successive pairs of holes is necessarily continuous, that is to say, after the completion of a group of attaching stitches through one pair of holes the work is at once shifted to bring another pair of holes into position to receive attaching stitches, the operation of forming attaching stitches continuing without interruption until all have been completed through both pairs of holes, after which, in some instances, the thread has been secured by a tying or knotting stitch. In machines of this type as heretofore constructed and operated, when passing from one row of holes to another the thread is laid across the face of the button in an exposed position where it not only presents an unsightly appearance but is easily broken, in which event there is nothing to prevent the unraveling of the stitches of the group first formed. Also, should the thread of the stitches of the second group formed be accidentally broken, the stitches of both groups are liable to unraveling, wholly or in part. In view of these difficulties, the type of single needle machine now generally in use is designed to sew the several groups of stitches through the respective pairs of holes in separate and distinct cycles of operation: in other words, in the use of such a machine, the machine is started and operated through a complete cycle to sew through one pair of holes a group of attaching stitches which may be completed by a tying stitch, after which the machine is brought to rest; the work clamp is then lifted to break the thread and is shifted to bring the other pair of holes into sewing position; and the machine is again started to perform a second cycle of operations during which a second group of stitches is sewn through the second pair of holes. Such division of the complete sewing operation into two separate steps or cycles, between which the machine is stopped, the work clamp lifted, and the machine again started, is inconvenient, time-consuming, and generally unsatisfactory.

The present invention has for its object to provide an entirely automatic single needle button sewing machine which, having been set in operation, will, before being brought to rest, perform and complete all of the operations necessary to form two groups of attaching stitches through two pairs of holes in a button, each group being separate and distinct, each being completed by a tying stitch independently of the other, and the thread being automatically severed between groups, so that there is no exposed, unsightly and readily broken line of thread extending across the face of the button between the rows of holes, and accidental breaking of the thread of the stitches of one group will not affect the integrity and security of the stitches of the other.

The invention will best be understood from the following description of certain illustrative embodiments thereof shown in the accompanying drawings, these, however, having been chosen for purposes of exemplification merely, as it will be obvious to those skilled in the art that said invention, as defined by the claims hereunto appended, may be otherwise embodied without departure from the spirit and scope thereof.

In said drawings:

Fig. 1 is a side elevation, partly broken away, of the complete machine.

Fig. 2 is a detail view illustrating the attachment of a four-hole button.

Figs. 3 and 4 are sections taken substantially on the lines 3—3 and 4—4, respectively, Fig. 1.

Figs. 5 and 6 are detail perspective views of the loop deflector and cooperating thread cutter, respectively.

Fig. 7 is a plan view, partly in section on the line 7—7 of Fig. 1.

Fig. 8 is a detail perspective view of the lower needle bar guide carrier.

Fig. 9 is a section taken on line 9—9 of Fig. 4.

Fig. 10 is a fragmentary plan view of the looper operating mechanism.

Fig. 11 is a plan view, and

Fig. 12 is a side elevation of the main cam.

Fig. 13 is a section on the line 13—13, Fig. 12.

Fig. 14 is a fragmentary plan view, partly in section, of the mechanism for controlling the looper mechanism in the formation of the tying stitch.

Figs. 15 and 16 are horizontal sections taken substantially on the lines 15—15 and 16—16 respectively, Fig. 1.

Figs. 17 and 18 are fragmentary detail views of

certain of the parts of the stop mechanism, showing them in different positions.

Fig. 19 is a fragmentary detail view of certain of the parts in Fig. 3.

Figs. 20 and 21 are detail sections taken substantially on the lines 20—20 and 21—21 respectively, Fig. 15, showing the parts in different positions.

Figs. 22 to 27 are detail views, partly in section and partly in front elevation, of the stitch-forming mechanism illustrating the operation during the attaching-stitch-forming cycle.

Figs. 28 and 29 are sections taken on the lines 28—28, Fig. 23, and 29—29, Fig. 24, respectively.

Figs. 30 to 36 are schematic views illustrating more in detail certain steps in the formation of the attaching stitches. Fig. 30 comprises, at the top, sectional perspective views of the thread clamp and take-up and front elevations of their respective cams, and, at the bottom, a fragmentary perspective view of the stitch-forming devices, showing the latter in the position corresponding to the positions of the thread clamp and take-up. Figs. 31 to 36 correspond to the bottom part of Fig. 30 and show the stitch-forming devices in different positions.

Figs. 37 to 44 are views similar to Figs. 22 to 27 illustrating the operation of the stitch-forming mechanism during the tying-stitch-forming cycle.

Figs. 45 to 49 are views similar to Fig. 30 illustrating certain steps in the completion of the tying stitch of one group of stitches and the initiation of the second group.

Fig. 50 is a view similar to Fig. 4, but showing the bed or horn in transverse section, illustrating a modified form of mechanism for operating the loop handling elements.

Fig. 51 is a longitudinal section taken substantially on the line 51—51, Fig. 50.

Fig. 52 is a fragmentary plan view, partly in section on the line 52—52, Fig. 51.

Fig. 53 is a detail perspective view of the loop deflector employed in the modification shown in Figs. 50 to 52.

For convenience the invention is herein illustrated in connection with a button sewing machine of the character shown and described in an application Serial No. 60,616, filed January 24, 1936, by Franklin A. Reece, and in order to make clear the purpose and operation of the mechanism to which the present invention relates, the general construction and operation of the machine of said application will be briefly outlined.

Referring to Figs. 1 and 3, the frame or casing of the machine comprises a base or bed 70 and an overhanging head 71 supported therefrom by an upright housing portion 72 enclosing the principal parts of the operating and controlling devices. For convenience of assembly and repair said frame or casing comprises two separable but normally connected main sections A' and A² and several attached minor parts all of which collectively afford the necessary enclosures, supports, bearings, etc., for the various moving parts.

The bed 70 carries a work plate 73 upon which the fabric W to which the buttons are to be attached is supported and against which it is clamped by a presser foot 74 carrying a button clamp 75 for holding the individual buttons B and positioning them for the operation of the sewing instrumentalities.

The main driving and controlling instrumentalities include a main power shaft 76 journalled in suitable bearings in the head 71 and to which power may be applied through a belt pulley 77.

under the control of automatic stop mechanism hereinafter described; a vertical cam shaft 78 journalled in suitable bearings in the housing 72, driven through a worm 25 and worm gear 26 from the main shaft 76, and provided with suitable cams for controlling the movements of the several instrumentalities; and a horizontal looper shaft 79 journalled in suitable bearings in the base 70 and operated and controlled from the cam shaft 78.

The stitch-forming instrumentalities include an eye-pointed needle 80, carried by a needle bar 81 mounted for vertical or longitudinal reciprocation in the head 71, and a pair of loopers 82 and 83 (Fig. 4) on a looper carrier 84 secured to the looper shaft 79 adjacent its forward end. The sewing thread t is supplied to the needle 80 from a suitable source, not shown, through a tension device or thread clamp 85 and suitably arranged guides on the head and needle bar and shown, for example, at 86 and 87, under the control of a take-up 88 operated by a cam 422 on the shaft 76, all as hereinafter further explained.

The needle bar 81 is longitudinally reciprocated from the main shaft 76 by any suitable means, as, for example, a crank pin 90 carried by a disk 89 on said shaft and connected by suitable linkage 91 with a collar 92 on said needle bar, and is guided adjacent its upper end in a bearing 93 which, as shown, is carried by a flexible metallic disk 94 suitably clamped in a recess 95 in the upper end of the head 71. This mounting of the needle bar guide 93 is such as to permit the needle bar a limited universal swinging movement about the point of intersection of its axis with the plane of the disk 94. Adjacent its lower end the needle bar is guided in a bearing 96 similarly mounted by means of a disk 97 in a carrier member 98 mounted, as hereinafter described, for movement in a horizontal plane both laterally and longitudinally of the machine frame.

In attaching a four-hole button B, as shown in Fig. 2, the carrier 98 is oscillated laterally between successive descents of the needle 80 to cause said needle to pass alternately through the holes h' and h2 in the button, the looper carrier being at this time oscillated laterally by the shaft 79 to cause the loopers to cooperate with the needle, as hereinafter more fully explained, in the formation of stitches s' passing through said holes. Thereafter the carrier 98 is shifted longitudinally, or in a direction fore and aft of the machine, to bring the needle into the plane of the holes h3 and h4 of the other pair, the looper shaft 79 with the looper carrier 84 and loopers 82 and 83 being similarly shifted to maintain the cooperative relationship of said loopers with the needle. Thereafter the sewing operations are repeated to form a second set of attaching stitches s2 passing through the holes h3 and h4.

The carrier member 98 for the lower needle bar guide 96 is guided for longitudinal movement in a groove in the top of a head 106 (Figs. 1 and 7) having a shank or trunnion 107 received in a socket 108 in the bottom wall of the head 71 of the machine, whereby said head 106 is pivoted for oscillation about the axis of said shank. Said carrier 98 is, therefore, free to move longitudinally in the head 106 or to oscillate laterally with said head about the pivotal axis of the latter.

The carrier 98 is oscillated laterally about the axis of the pivot 107 to cause the needle to pass alternately through the holes h', h2 or h3, h4, by mechanism more fully described in said Reece

application. Generally speaking, said mechanism comprises a link 113 (Fig. 7) suitably connected at one end with the carrier and provided at the opposite end with a stud 120 received in an arcuate groove 121 in one arm of a lever 122 secured to an upright shaft 123 journalled in the casing. At its opposite end the lever 122 carries a pin 125 which engages a cam groove 127 in the upper face of a main cam 129 (see also Figs. 1, 3 and 11) fast on the vertical cam shaft 78. With this construction it will be seen that rotation of the cam 129 will cause the lever 122 to swing about the axis of the shaft 123, and that this movement will be transmitted from said lever to the carrier 98 through the link 113.

The amplitude of the lateral vibration thus imparted to the carrier 98 will depend upon the point of engagement of the stud 120 with the groove 121, and in order to permit this to be readily adjusted in accordance with the lateral spacing of the holes in the button, the link 113 is provided with a third stud 130 engaged by a fork 131 carried by a slide 132 guided for horizontal movement on the side wall of the head 11.

The mechanism for moving the carrier 98 longitudinally is likewise shown in Fig. 7 and comprises a link 146 having at its forward end a stud 147 received in a transverse groove or way 148 in the upper face of the carrier 98 adjacent the rear end of the latter. The stud 147 also pivotally connects the link 146 with an arm 149 (see also Figs. 3 and 10) on a vertical rock shaft 150 journalled in suitable bearings on the interior of the main casing. At its rear end the link 146 carries a stud 151 which engages a groove 152 in an arm 153 secured to a second vertical rock shaft 154. Adjacent its lower end the rock shaft 154 has secured thereto an arm 155 having a bifurcated end between the branches of which is pivoted the end of a link 156 having a slot 157 to receive a stud 158 (see also Fig. 1) depending from a bracket or interior frame member 159 within the main casing. The link 156 is therefore, guided on the stud 158 by engagement of the latter with the slot 157 and is supported by a flange or head 160 (Fig. 3) on the lower end of the stud. The link 156 has secured thereto a pair of contact or cam follower blocks 161 embracing between them and cooperating with an edge cam 162 rotatably mounted on the stud 158 and the hub of which is provided with a spur gear 163 meshing with a pinion 164 on the lower end of the main cam shaft 78. The gear 163 and pinion 164 are of such sizes as to constitute two to one gearing between the cam 162 and the cam shaft 78, so that the cam 162 is rotated at one half the speed of the main cam 129. Accordingly, after one complete rotation of the cam 129 to cause the cam groove 127 thereof to produce a predetermined number of lateral reciprocations of the needle bar to form, for example, the group of stitches *s'* (Fig. 2), the cam 162 will cause the carrier 98 and needle bar to be shifted longitudinally of the machine in one direction, after which a second rotation of the cam 129 will cause the necessary number of lateral reciprocations to form the group of stitches *s2*, whereupon the cam 162 will return the carrier and needle bar to their original longitudinal positions.

The amplitude of the longitudinal or fore and aft movement of the carrier 98 and needle bar 81 is determined by the position of the stud 151 in the groove 152 of the arm 153, and, in order that this may be conveniently adjusted in ac-

cordance with the fore and aft spacing of the holes *h1*, *h2* and *h3*, *h4*, there is provided a fork 165 carried by a yoke 166 (Figs. 1 and 3) which is operated from the exterior of the casing by a hand lever 168 as more fully described in the Reece application above referred to.

The oscillations of the looper shaft 79 are effected through a slip coupling or clutch 178 and 180 (Fig. 10) and suitable connections including a link 190 (Figs. 1 and 3) provided with a transverse stud 191 the inwardly projecting end of which is received in an arcuate groove 192 (see also Fig. 10) in one end of a lever 193 fulcrumed at its opposite end on a stud 194 projecting inwardly from the side wall of the housing 12. Intermediate its ends the lever 193 carries a pin 195 engaging a cam groove 197 formed in the side or periphery of the main cam 129. The groove 197 corresponds to the groove 127, that is to say, the number and timing of the oscillations of the looper shaft 79 produced by the former correspond to the number and timing of the lateral oscillations of the needle produced by the latter. The amplitude of oscillation of the looper shaft 79 depends upon the position of the stud 191 in the groove 192 of the lever 193, and in order that this position may be suitably adjusted concurrently with the adjustment of the position of the stud 120 in the groove 121 of the lever 122, the slide 132 (Figs. 1, 3 and 7) by which the latter stud is adjusted is provided with a depending flange 202 having a slot 203 to receive the outwardly projecting end of the pin 191.

When the needle bar carrier 98 is shifted longitudinally, or in a direction fore and aft of the machine, in order to transfer the operation of the needle from the plane of one pair of holes, for example, the holes *h1*, *h2*, to the plane of another pair, for example, the holes *h3*, *h4*, the looper shaft 79 must be likewise shifted longitudinally to maintain the proper cooperative relationship of the loopers to the needle. This is effected by the vertical rock shaft 150 (Figs. 3, 7 and 10) whose arm 149 is connected with the link 146 by the pin 147. This rock shaft has secured to its lower end a second arm 204 (see also Fig. 1) connected by a link 205 with a fork 206 through openings in the arms of which the looper shaft 79 extends, and whose arms embrace a collar 207 secured to said looper shaft, whereby when the carrier 98 is shifted longitudinally by the lever 153 acting through the link 146, the shaft 79 will be correspondingly shifted longitudinally. It will be noted that the length of the arm 204 is greater than that of the arm 149 to compensate for the difference in distance from the pivotal center of the needle bar guide 83, of the shaft 79 and needle bar carrier 98, respectively.

The main cam 129 makes one complete rotation for each group of stitches *s'* and *s2*, and the number of stitches of each group depends upon the shape of the cam grooves 127 and 197. Referring to Fig. 11, the cam groove 127 is formed with five radially offset portions, adapted to produce five complete lateral reciprocations of the needle in synchronism with the vertical reciprocations thereof, and with a concentric portion 231 during which the needle is caused to make two descents through the same hole in the button in order to form a knot or tying stitch, as hereinafter further explained, it being understood that the groove 197 is correspondingly formed to produce the requisite cooperative os-

cillatory movements of the looper. Consequentially, each group of stitches will comprise ten attaching stitches and a tying stitch, the whole group requiring twelve vertical reciprocations of the needle.

The belt pulley 11 (Fig. 1) is loose on the shaft 18 and is adapted to be clutched thereto by a combined clutch and stop mechanism which as herein shown is similar to those shown and described in the patents to Mello, No. 1,227,643, May 29, 1917, and Reece No. 1,730,014, October 1, 1929. Referring to Figs. 17 and 19 to 21, said mechanism includes a ring 278 carried by the pulley 11 and having a pin 277 which projects through a slot 278 in said pulley and is engaged by a spring 279 located in a recess in said pulley, whereby said ring is permitted a limited yielding angular movement with respect to the pulley, in order to cushion the shock of starting. The ring 278 has a shoulder 280 adapted to be engaged by a clutch dog 281 pivoted at 282 to a hub 282 keyed to the shaft 18 and normally urged into engagement with said shoulder by a spring 283 connecting said dog with an arm 284 fixed to said hub. The dog 281 is formed with a stop arm 285 adapted, when the connected parts are rotated in the direction of the arrows on Figs. 19 to 21, to engage a head 287 yieldingly mounted by means of a spring 288 in the end of a stop arm 289 when the latter is in the position shown in full lines in Fig. 17, thereby disengaging the dog 281 from the shoulder 280 as shown in Fig. 20, and stopping the rotation of the shaft 18, the shock of stopping being cushioned by the spring 288. Recoil of the shaft under the influence of the spring 288 is prevented by a pawl 290 normally urged into a position to be engaged by a shoulder 291 on the hub 282 by means of a spring 292. The arm 289 is formed with a cam surface 293 which cooperates with a plunger 294 slidably mounted in the frame and engaging the pawl 290. The arrangement of the parts is such that, when the stop arm 289 is in the position shown in dot and dash lines in Fig. 17, the head 287 is out of the path of movement of the arm 285 of the dog 281, permitting the latter, under the influence of the spring 283, to engage the shoulder 280, as shown in Fig. 21, thereby connecting the pulley 11 and hub 282 for rotation in unison in the direction of the arrows. The cam surface 293 at the same time acts through the plunger 294 to hold the pawl 290 in the inoperative position shown in Fig. 21. When the stop arm 289 is in the position shown in full lines in Fig. 17, the head 287 will be engaged by the stop arm 285 to disconnect the parts and stop the machine, as above described. The cam surface 293 at this time permits the plunger 294 to be forced back by the spring 292, thereby permitting said spring to move the pawl 290 into operative position for engagement by the shoulder 291, as shown in Fig. 19.

The stop arm 289 is secured, as by a set screw 301, (Fig. 19), to a rock shaft 305 journalled in the frame and having secured thereto at the exterior of the casing an arm 306 (Figs. 1, 15 and 16) connected by a chain 295 (Fig. 1) with a suitable treadle (not shown), said arm being preferably provided with a spring pressed positioning plunger 296 adapted to engage either one of the two recesses or depressions 297 (Figs. 1 and 16) in the outer wall of the casing, thereby releasably retaining the stop arm 289 in either of the two positions shown in Fig. 17. To start the machine, the treadle is depressed, thereby

rocking the shaft 305 in the direction to move the stop arm 289 into the position shown in dot-and-dash lines in Fig. 17. The machine having been started will continue to operate until automatically stopped. For this purpose the following mechanism is provided:

Secured, as by a set screw 308 (Fig. 19), to the inner end of the rock shaft 305 is an arm 298 (see also Figs. 16 and 18) having a bifurcated end between the bifurcations of which is pivoted a bunter 299 having a bevelled free end 300 (Fig. 16) adapted, when said bunter is in the elevated position shown in Fig. 17 to be engaged by a stud 301 (Figs. 11, 12, 16 and 18) projecting from the underside of the main cam 129 when the latter reaches an angular position corresponding to the completion of a group of stitches of the number determined by the shape of the cam grooves 127 and 197. Such engagement of the end 300 of the bunter 299 by the stud 301 causes said bunter to be forced toward the right in Fig. 17, thereby rocking the shaft 305 in a clockwise direction and moving the stop arm 289 into the position shown in full lines in Fig. 17 to disengage the clutch and stop the machine. The stud 301 is preferably notched, as indicated at 302 in Fig. 11, so that the slight overthrow of the parts incidental to stopping the machine will bring said notch opposite the end of the bunter 299 (Fig. 16) in order to permit the machine to be again started by operation of the treadle.

The bunter 299 is normally drawn by a spring 304 into the inoperative position shown in Fig. 18 out of the path of movement of the stud 301, thereby permitting the continued operation of the machine after one complete rotation of the cam 129, until raised into its operative position by the following mechanism: Pivoted as at 309 (Figs. 17 and 18) to the frame member 159 is a bell crank lever having one arm 310 in engagement with a vertically sliding plunger 311 guided in said frame member and adapted, when raised, to lift the bunter 299 from the inoperative position shown in Fig. 18 into the operative position shown in Fig. 17. The other arm 312 of said bell crank lever engages a cam or eccentric 313 formed on the hub of the gear 163 and cam 162. The cam and gear assembly 162, 163, 313 makes one complete rotation to two completed rotations of the cam shaft 18 and main cam 129, and the eccentric 313 is so arranged that at the completion of one rotation of the cam 129 the bell crank 310, 312 and plunger 311 will be in the positions shown in Fig. 18, but at the completion of a second rotation of the cam 129 said parts will be in the position shown in Fig. 17, thereby lifting the bunter 299 into operative position and causing the stopping of the machine upon the completion of said second rotation.

Referring to Figs. 1, 30 and 45 to 49, the tension device 85 comprises two oppositely dished resilient disks 350 and 351 mounted on a rod 352 guided for longitudinal movement in a bushing 353 having an enlarged and recessed upper end upon which the lower disk 350 is supported, said bushing being in threaded engagement with the top of the head 71, whereby its vertical position thereon can be adjusted, and being secured in adjusted position in the latter by a lock nut 354. At its upper end the rod 352 is formed with a head 355 between which and the upper disk 351 is interposed a spring 356. Intermediate its ends, between the dished portions of the disks 350 and 351, the rod 352 is formed with an enlargement

357 of slightly less length than the space between said dished portions. At its lower end the rod 352 is formed with a head 358 which engages an edge cam 359 on the main power or needle shaft 76, said head being held in engagement with said cam by a spring 360 interposed between said head and a shoulder on the bushing 353. The thread *t* is received between the marginal portions of the disks 350 and 351, and when the rod 352 engages a high portion of the cam 359 and is moved thereby into the position shown in Fig. 47, the enlargement 357 lifts the disk 351 away from the disk 350, thereby releasing the thread. When the rod 352 engages a low portion of the cam 359, the spring 360 moves it into the position shown in Figs. 30, 45, 46, 48 and 49, whereupon the enlargement 357 releases the disk 351 and permits the latter to be pressed toward the disk 350 by the spring 353 whose strength is sufficient to exert a firm clamping pressure upon the thread. The cam 359 is formed with two low portions *a* and *b* and two high portions *c* and *d*. The shape of the cam and its angular position on the needle shaft 76 are such that when the needle starts downwardly from its uppermost position, the rod 352 is in engagement with the low portion *a*, thereby holding the thread clamped (Figs. 30 and 46). When, or just before, the needle enters the work (Figs. 31 and 47), the rod 352 is engaged by the high portion *c*, thereby releasing the thread, the shape and position of said portion *c* being such as to cause the thread to be in released condition when the needle enters work of the maximum thickness which the machine is intended to operate upon. When the needle approaches its lowermost position (Figs. 32 and 45), the rod 352 engages the low portion *b*, thereby causing the thread to be clamped. When, or just before, the needle reaches its lowermost position (shown in Fig. 33), the rod 352 engages the high portion *d*, thereby releasing the thread until the needle has started upwardly and its point has reached approximately the position shown in Figs. 23 and 26, after which the rod 352 engages the low portion *a* (Figs. 35, 36, 48 and 49), thereby causing the thread to be clamped and to be held clamped until the needle has reached its uppermost position and has moved downwardly into a position adjacent the work, as above explained.

The take-up 88 comprises a three-armed lever pivoted at 414 at the top of the head 71, said lever having an upright arm 416 formed with an opening or perforation 424 through which the thread passes between the tension device and the needle, a second arm 418 connected by a spring 419 with a pin secured to the wall of the head, and a third arm 420 engaged by the upper end of a plunger 421 slidably mounted in the top of the head and engaging at its lower end the periphery of the cam 422 on the main power or needle shaft 76. The cam 422 is formed with a descending portion *e* that causes the take-up to give up thread to the needle during the major portion of the descent of the latter (Figs. 30, 45 and 47), a short ascending portion *f* operative, as the needle approaches its lowermost position, to cause the take-up to withdraw a cast off loop from the loopers, as hereinafter explained, said ascending portion *f* being connected by a concentric portion *g* with a second ascending portion *h* operative, after the needle has left the work on its upstroke (Figs. 35, 36, 48 and 49), to cause the take-up to set the stitch.

The stitch-forming mechanism herein shown 75

is similar, with some modification, to the mechanism disclosed and claimed in an application Serial No. 64,693, filed February 19, 1936, by Joseph H. Pilul, and is as follows: Referring particularly to Figs. 4 and 22 to 29, the loopers 82 and 83 are formed with thread engaging shoulders *z* and are secured in fixed position on the looper carrier 84 which also carries a pair of loop spreaders 223 and 224 corresponding respectively to the loopers 82 and 83. The loop spreaders 223 and 224 are pivotally mounted in the carrier 84 and are normally held with their ends closely adjacent the ends of the loopers and in substantially the same vertical plane therewith, as shown in Fig. 28, by means of torsion springs 226 interposed between said carrier and tail portions 230 of said loop spreaders. Said loop spreaders are moved out of the latter positions to spread the thread loops by means of a cam plate 228 which, during the attaching-stitch-forming cycle, is held stationary, but which is formed with bevelled edges 229 adapted, as the looper carrier is oscillated, to engage the tail portion 230 of one or the other of the looper spreaders and move the same into loop spreading position, as shown in the case of the loop spreader 223 in Fig. 29.

The operation of the above mechanism in the formation of the attaching stitches is illustrated in Figs. 22 to 29. As above explained, the needle 80 is vibrated laterally between successive descents, causing the same to pass alternately through the holes *h'* and *h2*, or *h3* and *h4*, in the button, by the cam groove 127 in the cam 129, the looper shaft 78 and looper carrier 84 being oscillated in synchronism with the operations of the needle by the cam groove 197. At the beginning of the attaching operation, the needle descends through one of said holes, for example the hole *h'* shown at the left in Fig. 22, and through the work *W*, the looper carrier at this time moving toward the right from its extreme position toward the left. The needle then rises, leaving behind it a thread loop *l*, as shown in Fig. 23. The continued movement of the looper carrier toward the right causes the end of the looper 82, as well as the end of the corresponding loop spreader 223 (which at that time is immediately above said looper, as shown in Fig. 28) to enter said loop. The needle continues to rise, and the looper carrier continues to move toward the right, causing the loop *l* to be caught by the shoulder *z* of the looper 82 and carried into a position below the hole *h2*, as shown in Fig. 24. During this movement the tail 230 of the loop spreader 223 engages the left bevelled edge 229 of the cam plate 228, causing said spreader to be rocked about its pivot and carrying its end away from the looper 82, thereby spreading said loop, as shown in Fig. 29. The needle 80 is then moved laterally toward the right and again descends, this time passing through the hole *h2*, and in its descent passes through the spread loop *l*, the looper carrier simultaneously moving toward the left to cause the looper 82 and loop spreader 223 to release said loop which is thereupon drawn up about the needle and out of the path of the loopers, as shown in Fig. 25. The needle then rises, leaving behind it a second loop *l'* which, as the looper carrier 84 continues its movement toward the left, is immediately entered by the looper 83 and loop spreader 224 in a manner similar to the engagement of the loop *l* by the looper 82 and spreader 223 as above explained. Con-

tinued movement of the looper carrier into its extreme position toward the left causes the loop l^1 to be spread by the spreader 224 and caught by the shoulder z of the looper 83, so as to be carried into and held in a position in which the needle will pass therethrough during its next descent through the hole $h1$, thereby completing the first stitch which is set by a final operation of the take-up acting to draw the loop l^1 tightly up against the work after the needle has risen from and released said loop. These operations are continued to form a group of stitches s' , Fig. 2, of a number determined by the shape of the cam grooves 127 and 197.

A single stitch-forming cycle corresponding to one complete reciprocation of the needle (down and up), for example, the cycle immediately following the one last described, is illustrated more in detail in Figs. 30 to 36. The needle being in its substantially uppermost position, as shown in Figs. 27 and 30, and having been moved laterally into a position to pass through the hole $h1$, commences its descent, the thread being clamped by engagement of the head 358 with the low portion a of the cam 359, and the take-up 88 moving forwardly to release the thread to the needle by engagement of the plunger 421 with the descending portion e of the cam 422. As the needle eye is about to enter the work, as shown in Fig. 31, the head 358 is engaged by the high portion c of the cam 359, thereby opening the thread clamp and releasing the thread, the clamp preferably remaining open until the needle has descended through the hole $h1$, through the work W , and through the spread loop l^1 , into substantially the position shown in Fig. 32. By reason of the complete release of the thread during this period, the needle is enabled to draw from the supply a length of thread automatically and accurately measured in accordance with the spacing of the holes $h1$, $h2$, the thickness of the button B , the thickness of the work W , and the length of neck n connecting the button with the work. This thread-measuring operation of the needle forms the subject matter of a separate application Serial No. 175,651, filed November 20, 1937, by Joseph H. Pikul. As the needle advances from the position shown in Fig. 32 toward that shown in Fig. 33, the looper 83 and loop spreader 224 move toward the right to release the loop l^1 as shown in Fig. 33. At this time the head 358 is engaged by the low portion b of the cam 359, thereby causing the thread to be clamped, after which the plunger 421 is engaged by the ascending portion f of the cam 422, causing the take-up 88 to move backwardly and thereby withdraw the loop l^1 out of the path of movement of the loopers and up about the needle as shown in Fig. 33, this operation being assisted by the continued downward movement of the needle. Meantime the needle has descended to substantially its lowermost position and thereafter rises to leave behind it another loop l^2 as shown in Fig. 34. Since, during the latter part of the descent of the needle, the thread has been firmly clamped and has been subjected to the action of the take-up, it is placed under a substantial tension and has been resiliently stretched to a certain extent. In order to prevent this tension, and the consequent stretch of the thread, from interfering with the throwing out of the loop l^2 , the clamp is opened to release the thread, as soon as the loop l^1 has been drawn into the position shown in Fig. 33, by engagement of the head 358 with the high por-

tion d of the cam 359. Meantime, the looper carrier 84 has been moving toward the right, and, when the loop l^2 has been sufficiently opened by the rise of the needle, the looper 82 and loop spreader 223 enter said loop as shown in Fig. 34. At this time the head 358 is engaged by the low portion a of the cam 359, causing the thread to be clamped, the loop spreader 223 is operated to spread the loop l^2 , as above explained and as shown in Fig. 35, and, after the needle has risen from the work, the plunger 421 is engaged by the ascending portion h of the cam 422, thereby causing the take-up 88 to draw the loop l^2 firmly up against the work and set the stitch as shown in Fig. 36.

At the completion of the group of attaching stitches, the needle is caused to descend twice through the same hole in the button, due to the concentric portion 231 of the cam groove 127, during which the looper mechanism, together with certain associated parts about to be described, operates in such a manner as to form a tying stitch or knot and sever the thread.

Referring to Figs. 1, 4, 9 and 14, the cam plate 228 is secured, as by riveting, to a sleeve 232 (see particularly Fig. 9) mounted to turn on a reduced end portion 233 of the looper shaft 79, while the looper carrier 84 has a hub portion 234 secured, as by pins 235, to said reduced portion. The cam plate 228, while free to turn on the shaft, is held against movement longitudinally thereof, in one direction by engagement of said cam plate with the looper carrier 84, and in the opposite direction by engagement of the end of the sleeve 232 with a shoulder 236 at the end of the reduced portion 233. Mounted to turn on the hub 234 of the looper carrier is a loop deflector carrier 237 which is retained on the shaft by a nut 238. The cam plate 228 and loop deflector carrier 237 are connected with one another, for turning movement in unison about the axis of the looper shaft, by a pin 240 connected by a link 244 with a pin 245 carried between the ends of a pair of arms 246 (Figs. 1, 4 and 14) projecting from a hub 247 secured, as by a pin 248, to a shaft 249 suitably journalled in the frame and extending parallel to the looper shaft 79. The spacing of the arms 246 relative to the width of the link 244 is sufficient to permit the above described longitudinal movement of the looper shaft and the parts carried thereon without corresponding movement of the shaft 249. The shaft 249 (see particularly Figs. 4 and 14) is provided adjacent its inner end with a skew gear 250 which meshes with a skew gear 251 on the lower end of an upright shaft 252 suitably journalled in the frame and having secured to its upper end, as by a pin 253, a head 254. The head 254 carries a pin 255 which engages a cam groove 257 (see also Fig. 13) formed in the bottom of the main cam 129.

Secured, as by bolts 36, to the carrier 237 is the shank 267. (Figs. 5 and 37 to 42) of a loop deflector 268, said shank being of such a shape that, as said carrier is oscillated about the axis of the looper shaft 79, the loop deflector 268 will move in an arcuate path immediately over the loopers and loop spreaders. Said loop deflector is formed with a neck portion 269 sufficiently narrow to permit the needle to pass at one side thereof and has a notched end 270 adapted to engage one leg of a needle loop. Adjustably secured, as by screws 367 (Fig. 4), to the looper carrier 84 is the shank 368 (Fig. 6) of a cutter

369 having its edge directed toward the loop deflector 268.

The cam groove 257 (Fig. 13) is for the most part concentric but includes an operative portion 272 so arranged as to be engaged by the pin 255 when the pin 125 is in the concentric portion 231 of the groove 127. The form of the cam groove portion 272 is such as to cause two oscillations of the cam plate 228 and loop deflector carrier 237 during two stitch-forming cycles in the course of which the needle makes two descents through the same hole in the button, as above explained, the second oscillation being of greater amplitude than the first. The cam groove 197 (Fig. 12) is formed with portions 274 and 275, offset in the same manner as the portions producing the attaching-stitch-forming oscillations of the looper but to a lesser extent and of less angular length. The arrangement is such that the pin 195 engages the cam groove portions 274 and 275 when the pin 125 is in the concentric portion 231 of the groove 127 and when the pin 255 is in the operative portion 272 of the cam groove 257.

The operation of the parts in the formation of the tying stitch is illustrated in Figs. 37 to 46. After the formation of the last loop of the group of attaching stitches, for example, the loop *lx* formed by the descent of the needle through the hole *h2*, the needle again descends through the other hole, for example the hole *h'* shown at the left in Figs. 37 and 38, and through said loop *lx* (while the latter is held by the looper 83 and loop spreader 224), and thereafter rises, leaving behind it a loop *la* as shown in Fig. 39. Simultaneously the looper carrier moves, first toward the right (Fig. 38) to cause the looper 83 and loop spreader 224 to release the loop *lx*, and then, under the influence of the cam groove portion 274 (Fig. 12) toward the left to cause said looper and loop spreader to enter the loop *la*, as shown in Fig. 39. During the latter movement the cam plate 228, under the influence of the operative portion 272 (Fig. 13) of the cam groove 257, also moves toward the left, following the movement of the loop spreader 224 so that there is at this time no loop-spreading actuation of the latter, and its entry into the loop *la* with the looper 83 is facilitated. Thereafter, as the needle rises, said operative cam groove portion 272 causes the cam plate 228 and the loop deflector carrier 237 to be turned toward the right, thereby causing the loop spreader 224 to spread the loop *la* and the notched end 270 of the loop deflector 268 to engage one leg of the loop and deflect the same, as shown in Figs. 40, 41 and 45. This movement of the loop deflector, as indicated in Figs. 40, 41 and 45, is of insufficient extent to carry the deflected leg of the loop *la* into engagement with the cutter 369. The needle thereupon descends again through the same hole *h'* and through the loop *la*, which is thus held open and in a position to receive it, as shown in Figs. 41 and 45. The looper carrier 84 then moves toward the right and the deflector carrier 237 toward the left, causing the looper 83, loop spreader 224 and loop deflector 268 to release the loop *la* and cast the same about the needle as shown in Fig. 42. The needle then rises, leaving behind it a loop *lb* which is entered by the looper 83 and loop spreader 224, by reason of movement of the looper carrier toward the left under the influence of the cam groove portion 275 (Fig. 12), as shown in Fig. 43, the cam plate 228 again partaking of this movement, as above described in connection

with Fig. 39. The cam plate 228 and loop deflector 268 thereupon again move toward the right, as shown in Fig. 44, this movement being of greater amount than the first movement, so that the loop deflector forces the engaged leg of the loop *lb* against the edge of the cutter 369 and severs the same, as shown in Figs. 44 and 46, the leg thus severed being the one leading through the loop *la* from the previously formed stitches.

The operations thus far described may, as indicated in Figs. 30 to 36, 45 and 46, be considered as those involved in the formation of the first group of stitches *s* through the holes *h'* and *h2*. The severance of one leg of the loop *lb* by the combined action of the loop deflector 268 and cutter 369, as shown in Fig. 46, takes place relatively close to the work, and the remainder of the thread of that leg, as well as that constituting the other leg of the loop *lb*, extends from the point of severance and the end of the then advanced loop deflector around the then separated looper 83 and loop spreader 224, and thence through the loop *la* to the needle and thread supply. The combined action of the looper, loop spreader and loop deflector in opening and positioning the loop *lb* has caused said loop to include a considerable length of thread the major portion *v* of which, after the thread has been severed, is included in the thread which leads from the thread supply through the needle eye and work. This portion of the loop *lb*, the length of which is indicated at *w* in Fig. 47, after severance falls away from the loopers and depends from the loop *la*, as indicated in the latter figure. The needle and loopers are then moved into the plane of the second pair of holes *h3*, *h4*, the resulting deflection of the thread causing a very short portion, indicated at *x* in Fig. 47, of the loose end *v* to be withdrawn through the loop *la*. During the first descent of the needle through the hole *h3* into the position shown in Fig. 22, in the initiation of the second stitch group, the thread end *v* remains in substantially the position shown in full lines in Fig. 47. As the needle rises from the position shown in Fig. 22 after its first descent, the looper 82 and loop spreader 223 enter the resulting loop *lc* (Fig. 48) and position and spread said loop as shown in Figs. 24, 29 and 48. This positioning and spreading of the loop requires additional thread which, the thread leading from the supply being at this time clamped, is drawn from the thread end *v* to substantially the extent indicated at *y* in Fig. 48. Thereafter, as the needle continues to rise, the loose thread end *v* is completely withdrawn over the "bridge" (or portion of the button separating the holes *h'* and *h3*), as shown in Fig. 49, due to the rise of the needle, the change in angularity of the thread between the thread guides, and the final action of the take-up which, in the normal stitch-forming cycle, acts to set the stitch, but which at this time, since there is no stitch to set (i. e., no loop to be drawn up to the work), acts directly upon the trailing end of the thread and assists in the complete withdrawal of the latter from the loop *la*, the hole *h'* and the face of the button.

In Figs. 50 to 53 is shown a more compact arrangement of the mechanism for operating the loop deflector and loop spreader cam plate, which mechanism is designed for use in machines in which the base or bed is in the form of a horn 70a of sufficiently small cross-section to be received within a coat sleeve or the like. In this arrangement the sleeve 232, which carries the

cam plate 228, has rotatably mounted thereon a second sleeve 362 to which is fixed a plate 361. The loop deflector 268b is formed integral with its carrier 237b which is secured by bolts 360 to the plate 361, said bolts passing through arcuate slots 363 in the carrier 237b, whereby the angular position of the deflector with respect to the sleeve 362 may be adjusted. The sleeves 232 and 362 are provided with gear segments 364 and 365 which mesh with complementary gear segments 366 and 367 on the shaft 249, the relative radii of the several segments being such as to turn the sleeve 362 through a greater angle than the sleeve 232, since the angular movement necessary to cause the cam plate 228 to spread the loop spreaders during the tying stitch forming operation is less than that required of the loop deflector to enable the latter to effect its several functions. The mechanism is otherwise substantially the same as that first described, and its operation will be understood without further explanation. It may be noted, however, that, by reason of the gear connections described between the shaft 249 and the parts operated thereby, the direction of the movements imparted to the shaft 249 by the cam groove 251 through the shaft 252 should be opposite to those in the arrangement shown in Fig. 4 in order to produce the same movements of the loop deflector and cam plate. This may be accomplished by an opposite inclination of the teeth on the gears 250a and 251a, as shown, or by a different mechanical connection between the shafts 249 and 252, for example, that more fully described in application Serial No. 117,550, filed December 24, 1936, by Samuel W. Avis, or otherwise as the precise mechanical connections employed for transmitting rocking movement from the shaft 252 to the shaft 249 form no portion of the present invention and may be designed to suit convenience.

We claim:

1. In a machine for sewing on buttons, the combination with stitch-forming devices including a needle and a cooperating looper, and mechanism for operating said stitch-forming devices to form groups of stitches, of an additional element cooperating with the looper to form a tying stitch, and means for operating said element only at the end of the formation of a stitch group to position a thread loop held by the looper for the passage of the needle therethrough in the formation of a tying stitch and thereafter cause severance of the thread.

2. In a button sewing machine, sewing mechanism for forming a plurality of groups of stitches, said mechanism including a needle, looper elements cooperating with said needle, and means for positioning a loop for the passage of the needle therethrough, said last named means including a loop deflector and means for operating the same to position a loop and to sever the thread upon the completion of each stitch group.

3. In a machine for sewing on buttons, in combination, stitch-forming devices including a needle and cooperating loop-taking means, actuating and controlling mechanism for causing said stitch-forming devices to sew, in a continuous operation, a plurality of groups of stitches, an element adjacent the loop-taking means, and means whereby said element is caused to first cooperate with said needle and loop taking means for the formation of a tying stitch at the end of the first stitch group and then sever the

thread while the operation of the machine continues.

4. In a machine for sewing on buttons, in combination, stitch-forming devices including a needle and a looper for taking thread loops formed by said needle, mechanism for operating said stitch-forming devices to form groups of stitches, a member for positioning a loop taken by said looper for the passage of said needle therethrough, a thread severing element, and means for operating said member to position a loop and thereafter to move the thread against said element to effect severance of said thread upon the completion of a group of stitches.

15 5. In a machine for sewing on buttons, in combination, stitch-forming devices including a needle, a looper for taking thread loops formed by said needle, and a member for positioning a loop taken by said looper for the passage of said needle therethrough, mechanism for operating said stitch-forming devices in a continuous cycle to form consecutively two groups of stitches, and a cutter against which the thread is moved by said loop positioning member to sever the thread upon the completion of the first group of stitches while the operation of the machine continues.

20 6. In a machine for sewing on buttons, in combination, stitch-forming devices, mechanism for operating the same to form a group of stitches completed by a tying stitch, said stitch-forming devices including a needle and a member for positioning a thread loop for the passage of said needle therethrough in the formation of a tying stitch, and a cutter against which the thread is moved by said loop positioning member to sever the thread upon the completion of the tying stitch.

35 7. In a machine for sewing on buttons, in combination, stitch-forming devices, mechanism for operating the same to form a group of stitches completed by a tying stitch, said stitch-forming devices including a needle, a looper for taking thread loops formed by said needle, and a member for positioning a loop taken by said looper for the passage of said needle therethrough in the formation of the tying stitch, and a cutter against which the thread is moved by said loop positioning member to sever the thread upon the completion of the tying stitch.

40 8. In a machine for sewing on buttons, in combination, stitch-forming devices, mechanism for operating the same in a continuous cycle to form consecutively two groups of stitches each completed by a tying stitch, said stitch-forming devices including a needle, a looper for taking thread loops formed by said needle, and a member for positioning a loop taken by said looper for the passage of said needle therethrough in the formation of the tying stitches, and a cutter against which the thread is moved by said loop positioning member to sever the thread upon the completion of the tying stitch of the first group and while the operation of the machine continues.

55 9. In a machine for sewing on buttons, in combination, stitch-forming devices, mechanism for operating said devices to form groups of stitches each completed by a tying stitch, a thread-severing element, a loop-positioning member, and means for causing said member to first cooperate with said devices to form a tying stitch and then move the thread against said element to effect severance of the thread.

70 10. In a button sewing machine, the combination of a needle and an oscillatory carrier having

two sets of loop-handling elements for alternate cooperation with the needle in the formation of attaching stitches; a thread cutter mounted on said carrier out of reach of a loop being handled by either set of elements; and a deflector movable to position a loop being handled for penetration by the needle in the formation of a tying stitch and further movable to force the thread of a loop being handled into cutting engagement with the cutter.

11. In a button sewing machine, the combination with stitch forming devices and mechanism for operating the same to form groups of attaching stitches, of a thread handling element and means for causing the same to cooperate with said stitch forming devices to form a tying stitch upon the completion of a group of attaching stitches, and an additional element cooperating with said thread handling element to sever the thread.

12. The combination in a sewing machine having a work holder, sewing instrumentalities, means for actuating said instrumentalities to form stitches, means for relatively moving said instrumentalities and holder during a single machine operation to place stitches in two sets spaced apart in work held by said holder each set being completed with a plurality of tying

stitches, and means acting to clamp the sewing thread after the first set of stitches has been placed, of a finger, and means to actuate said finger to cause parts including said finger to sever the sewing thread adjacent to the work while the thread is clamped and in position to complete the tying of the thread at the end of the stitching of the first set.

13. The combination in a sewing machine having a work holder, sewing instrumentalities, means for actuating said instrumentalities to form stitches, means for relatively moving said instrumentalities and holder during a single machine operation to place stitches in two sets spaced apart in work held by said holder and ending with a plurality of knotting stitches, and means acting to clamp the sewing thread after the first set of stitches has been placed, of a knife, and means actuatable to cause said knife to sever the sewing thread adjacent to the work while the thread is held clamped and in position to complete the tying of the thread at the end of the placing of the stiches of the first set.
